UNITED STATES PATENT OFFICE.

BENJAMIN SIEGEL, OF DETROIT, MICHIGAN.

DELIVERY-BOX.

1,126,893.

Specification of Letters Patent.

Patented Feb. 2, 1915.

Application filed November 1, 1913. Serial No. 798,616.

To all whom it may concern:

Be it known that I, BENJAMIN SIEGEL, a citizen of the United States of America, residing at Detroit, in the county of Wayne and State of Michigan, have invented certain new and useful Improvements in Delivery-Boxes, of which the following is a specification, reference being had therein to the accompanying drawings.

10 The invention relates to boxes such as are used for the packing and delivery of articles sold in sets in retail stores, such for instance as furs.

15 It is the object of the invention to provide a receptacle in which all of the articles belonging to the set are inclosed, while at the same time they are held in separate compartments, so that one will not be crushed or injured by another. This I have 20 accomplished by the construction as hereinafter set forth.

25 In the drawings: Figure 1 is a perspective view partly broken away of my improved delivery box; Fig. 2 is a cross section through the cover, tray and supporting ledge; and Fig. 3 is a plan view of one corner of the box with the tray and cover removed.

30 A is a rectangular paper board box, which is provided with a cover B having depending flanges C.

35 D is a ledge formed within the box and extending around the sides thereof. This is preferably formed of wooden strips which are glued or otherwise attached to the box sides, as shown in Fig. 3.

E is a tray formed of paper board and

resting upon the ledge D, preferably so that the upper edges of its flanges are flush with the top of the box body.

40 F are loops secured to the tray E, to facilitate the withdrawal of the same from the box body.

45 In use a set of articles to be delivered,— such for instance as a fur muff and scarf, may be packed in the box by first removing the cover and tray and placing the larger article in the bottom of the box; then replacing the tray with the smaller and lighter article therein, and then placing on 50 the cover. The same construction may be used for various other articles which are sold in sets, and will be equally useful in protecting them from injury. The strips D in addition to their function of forming a 55 support for the tray constitute reinforcements or strengthening ribs which add to the strength of the package.

What I claim as my invention is:

60 A delivery box, comprising a rectangular paper board body, a ledge formed of wooden strips secured to the inner sides of the body, a paper board tray supported on said ledge having its flanges flush with the top of the body, and a flanged cover for 65 said body and tray, said cover holding said tray from vertical movement.

65 In testimony whereof I affix my signature in presence of two witnesses.

BENJAMIN SIEGEL.

Witnesses:

JAMES P. BARRY,
W. K. FORD.
